UNITED STATES PATENT OFFICE.

MAURICE C. CLARK, OF PROVIDENCE, RHODE ISLAND, ASSIGNOR TO MARVEL RUBBER COMPANY, A CORPORATION OF RHODE ISLAND.

ARTICLE OF VULCANIZED FOOTWEAR.

No. 926,387.

Specification of Letters Patent.

Patented June 29, 1909.

Application filed October 28, 1905. Serial No. 284,843.

To all whom it may concern:

Be it known that I, MAURICE C. CLARK, a citizen of the United States, and a resident of Providence, county of Providence, and State 5 of Rhode Island, have invented a new and useful Article of Vulcanized Footwear, of which the following is a specification.

My invention consists in a vulcanized shoe or boot as an article of manufacture containing 10 the features and combinations of features hereinafter particularly described and specifically set forth in the claims.

In the following is described not merely the features of the article itself, but also the 15 process by which it is preferred to manufacture the same.

In the accompanying drawings, Figures 1 and 2 represent an overshoe containing the 20 invention. Figs. 3 to 6 are various sections of the same. Figs. 7 and 8 are details illustrating methods of building. Figs. 9, 10 and 11 are diagrammatic representations of the molding and vulcanizing operation. Fig. 12 is a longitudinal section of a lumberman's 25 shoe containing the invention.

The shoe or boot may be built upon the last as follows: Upon the last 1, is first placed the insole 2; next, the lining 3 with its lower edge lapping the insole, as shown; next, the 30 filling sole 4; next, the upper 5; next, the outsole 6.

The lining 3 and insole 2 are composed of textile material coated on the outside with rubber. They are preferably partially vulcanized before being built upon the last, 35 although they may be built upon the last in unvulcanized condition. This partial vulcanization may be performed by subjecting the coated textile fabric for the lining and insole to a lower degree of heat (say, 240 degrees), or for a shorter length of time, than would ordinarily be used for the vulcanization of the rubber compound. The effect of 40 this preliminary partial vulcanization of the lining material is that the creeping on the surface of the last under the outside mold pressure is less. Moreover, the partial vulcanization has a tendency to prevent the substantial pressure between the last and 45 outside mold from striking or forcing the outside rubber compound of the upper through the textile material of the lining so as to coat the inner surface thereof with the rubber compound.

50 The filling sole 4 is of textile material

coated on both sides with unvulcanized rubber compound. The upper 5 is a sheet of unvulcanized rubber compound which is preferably slightly thicker than desired in the finished article, because the pressure of 60 the molds has a tendency to thin it by crowding its material toward and, to some extent, out at the edges of the mold parts. The upper in the completed article is preferably gradually thickened at 5^a as it approaches 65 the sole, all the way around the shoe. For the production of this thickening, dependence may be placed upon the crowding or flowing of the rubber compound toward the edge above referred to, or the unvulcanized 70 sheet may be made thicker at that point before being built on the last.

The outside sole 6 is made of less than the full width or length and built, as shown either in Fig. 7 or Fig. 8, wherein the upper 75 extends down into the sole space of the mold so that the material of the upper shall, in the finished article, constitute the outer edge of the sole.

In Fig. 7 the edge of the unvulcanized 80 sole is shown as abutting against the side of the unvulcanized upper, but in Fig. 8, the upper is shown as containing an extension under the sole and forming a beveled joint therewith. An advantage of building, 85 as shown in Figs. 7 and 8, is that in the completed article the superior composition (containing a larger percentage of real rubber and being softer when vulcanized) of the upper extends all the way down to the bottom of the shoe and the inferior composition of the sole is confined to the middle portions of the sole; presenting a superior quality of material at the edges of the sole where the joint occurs with the upper and the cracking 90 tendency of the upper is greatest and where the sole receives most blows in wear.

In the building of the shoe above described, the upper is a separately rolled sheet of rubber compound from the rubber 100 coated lining. This, while preferable, is not essential because the sheet constituting the upper may be rolled onto the coated lining before the lining is applied and the two applied together. In this case, preferably the 105 coated lining will be partially vulcanized as above described before the unvulcanized sheet constituting the upper is rolled onto it.

After the building of the shoe in any of the ways above described, a vamp piece of fine 110

grade of rubber compound may be applied as shown in Figs. 1 and 2 in dotted lines, forming a zone of superior rubber extending over the instep from sole to sole, and from the top of the vamp a portion of the distance toward the toe. It thus covers the portions of the rubber that are most liable to wrinkle and to crack. Again, the ball of the sole may be covered by a thin piece of fine grade rubber compound, as indicated at 8, in Figs. 2 and 3. Again, the rear portion of the heel may also be covered by a thin piece of fine grade rubber compound, as indicated at 9, Figs. 2 and 3. Again, the superior compound of the upper forming the edge of the sole, as shown in Fig. 8, after vulcanization, extends below the lower level of the sole entirely around the shoe, so as not only to relieve the bottom of the sole from wear but also to present a head or series of projections of comparatively soft and superior rubber which will prevent the wearer from slipping.

After building the shoe upon the last in the manner above described, it, still containing the last, is placed within the mold for purposes of vulcanization; dependence being placed upon the form of the interior of the mold to give the final form and finish to the completed article and impress upon it any lines or marks, such as corrugation of the sole, etc.

The molding step of the process is as follows: Reference is made to the diagrams Figs. 9, 10 and 11, in which A represents the inverted last (of solid or rigid material such as wood or metal in contradistinction to gaseous material, such as air) with a shoe built upon it as above described, at a cross section at about the ball of the foot. B and C are two side parts of the mold having motion toward and from each other. D is the sole mold having motion toward and from the two side molds.

According to the preferable method, the shoe and last are supported slightly above the vulcanizing position (about $\frac{1}{4}$ of an inch above) and the side molds B and C are brought together, as shown in Fig. 9. Then the sole mold is advanced so as to press the shoe and its last down into vulcanizing position, as shown in Fig. 10. By this mode of operation, as the side molds are brought together, the presence of the space a inside their edges prevents them from having any substantial chafing action upon the shoe which would cause the lining to creep on the last so as to form a fold in the lining between the edges of the mold at the junction of the side molds. The final motion from the position of Fig. 9 to that of Fig. 10, by which the last and shoe are forced down into the side molds, is so slight as either not to produce any substantial creeping of the lining on the last at the sides of the shoe; or if such creeping occurs, any resulting fullness of the

lining is substantially at the junction between the lining and the sole where it is substantially negligible. It will be observed that the upper edges of the side molds B and C are slightly beveled so as to leave spaces b, c adjacent to the edges of the sole. The rubber forced into these spaces by the compression of the upper (or placed there in building the shoe, as above described) forms the thickening of the upper adjacent to the edges of the sole above referred to and shown in Figs. 3 to 6. The molds being heated to vulcanizing temperature as soon as their heat is brought to bear upon the unvulcanized rubber of the upper, it is almost immediately softened to such an extent that it tends to flow away from the regions of greatest pressure toward the regions of less so as to fill up any cavities provided by the mold.

It will be understood, of course, that Figs. 9, 10 and 11, are merely diagrammatic and the spaces a, b and c are exaggerated in size for convenience of illustration.

In lieu of employing the preliminary position or movement illustrated in Fig. 9, the closing of the molds may, though less desirably, be accomplished all at once, as shown in Fig. 11. That is to say, the last and shoe A may be held in its final vulcanizing position while the side molds B and C and sole mold D are all closed at once. In this case, for the prevention of the formation of a fold of the lining between the side molds B, C, dependence must be had upon the fact that the final junction of the molds B and C occurs at a line d from which the curvature of the upper on each side is sufficiently abrupt, so that the molds move only a very short distance from the time that they come in contact with the surface of the upper until they come in contact with each other and, therefore, there is very little tendency to cause the lining to creep upon the surface of the last toward the line d. Such creeping tendency is also decreased if the lining has received the preliminary partial vulcanization above referred to.

In the vulcanized article produced by the molds of Figs. 9 and 10, the upper, inclusive of the preferable extra thickness thereof produced in the spaces b and c will overlap the edges of the sole so that practically the upper extends down to the ground. Or, in other words, the sole is edged all around by the material of the upper, which is considered to be a great advantage because it produces a joint between the upper and the sole that is not likely to give way, and also produces a sole that will wear better at the edges. If the material of the upper extends below the sole it may serve to prevent slipping and to relieve the middle of the sole from wear.

In case the heel or outsole is built up of more than one layer or tap, as in the case of a boot or a lumberman's shoe, shown in Fig. 12, the material of the upper will be extended

to the bottom of the sole and heel inclusive of any tap that the sole or heel may contain. In Fig. 1 is shown the shoe provided with a rib or bead r extended across the front of the 5 vamp from the opening of the shoe to the toe portion of the sole, while a second rib or bead r' extends downward at the heel. Both these beads r and r' are formed at the junction of adjacent or inner edges of the side 10 molds, and in addition to giving strength and durability to the shoe also add to the appearance of the article.

Having thus described my invention, I claim as new and desire to secure by Letters 15 Patent:—

1. A vulcanized article of molded rubber footwear comprising a textile lining, an insole, a rubber outsole, and a rubber upper directed toward and united with the sole, 20 the lower edge of said upper constituting the outer edge of the sole and being of softer composition than the body portion of the sole.

2. A vulcanized article of molded rubber 25 footwear comprising a sole member and an

upper extending down to and under the edge of the outsole forming a union with the same, and a molded projection or bead extending around the bottom of the sole.

3. A vulcanized article of molded rubber 30 footwear, comprising a sole portion and an upper having its lower edge extending down to and under the edge of the outsole, and forming a union therewith, the edge of the upper being of softer material than the central portion of the sole. 35

4. A vulcanized article of molded rubber footwear, comprising a textile lining, an insole, an outsole, an upper having the lower edge portion overlapping and extending in 40 toward the center of the outsole, and united with said outsole, and a projection at the edge of the outsole.

In testimony whereof I have signed my name to this specification in the presence of 45 two subscribing witnesses.

MAURICE C. CLARK.
